Application July 21, 1943, Serial No. 495,548

35 Claims.

(Cl. 179—5)

This invention relates to communication systems, and, more particularly, to communication systems of the type suitable for use by fire or police departments.

Fire and police departments require communication systems which have as a prime characteristic service reliability together with certain desired features, such as simple and rapid communication between a control station and any one of a plurality of selected outlying stations. In order to provide the service reliability, certain spare or duplicate equipment parts are provided at the control station, and at both the control station and the outlying stations emergency power supplies are provided. Preferably the shift from one set of equipment to the spare or duplicate equipment is brought about automatically together with a notification to the attendants of such change. Each emergency switching operation is preferably automatic, and associated facilities are provided which require acknowledgement by the attendants to insure proper attention, thus guarding against neglect to correct the abnormal conditions. In order that the telephone lines between the control station and the outlying stations provide reliable service, it is desirable to provide continuous line-short and line-open tests together with frequent periodic ground tests for each line, together with suitable signals audible or visual or both, which must be acknowledged by the attendants.

In providing communication between the control station and the outlying stations it is desirable to provide telephone communication between an outlying station and the control station. The telephone communication, however, must be subjected to the priority demands of a loudspeaking communication system by which the control station may notify any one or a plurality of outlying stations of certain conditions, such as a fire, which require action and response on the part of the attendants at the outlying stations. In providing loudspeaker communication in such a system it is desirable to provide a simple yet reliable connection between the control station amplifier and one or more of the outlying station telephone lines.

It, therefore, is an object of the present invention to provide an improved communication system between a control station and a plurality of outlying stations, wherein reliable operation is provided by providing continuous tests for open-circuit and short-circuit conditions on the telephone lines.

It is another object of the present invention to

provide an improved communication system wherein each conductor of the various telephone lines interconnecting the control station with a plurality of outlying stations is periodically tested for ground.

It is another object of the present invention to provide periodic tests of the operativeness of the loudspeaking communication system between a control station and a plurality of outlying stations together with certain signal arrangements which require an acknowledgement on the part of the attendants at each of the outlying stations.

It is another object of the present invention to provide a loudspeaking telephone communication system between a control station and a plurality of outlying stations wherein one or more lines to outlying stations may be readily connected to an amplifier at the control station without the use of special isolating devices or circuits.

It is a still further object of the present invention to provide a loudspeaking communication system between a control station and a plurality of outlying stations whereby communication may be had with a certain outlying station, communication may be had with a group of outlying stations, communication may be had with a certain station or group of stations together with a common group of stations, and communication may be had with all stations associated with the system.

Still another object of the present invention is to provide combined telephone and loudspeaking communication between a control station and a plurality of outlying stations wherein the loudspeaking system takes precedence over the usual telephone communication facilities by automatically removing the telephone set at the control station and the outlying station when loudspeaking communication is being used.

Still another object of the present invention is to provide reliable communication service between a control station and a plurality of outlying stations, each of which is provided with auxiliary power equipment arranged to be automatically switched on or switched into service upon failure of the regular equipment and an indication or alarm is to be given which requires acknowledgement on the part of the attendant at the station.

In accordance with the present invention individual telephone communication is provided between a control station and an outlying station. Either station may signal the other station that

telephone communication is being desired. In addition loudspeaker communication is provided between the control station and each or all of the outlying stations. While many of the features of the system to be disclosed herein may be used for various purposes they will be described, to show one practical application, as being applied to a fire department. The control station is provided with regular and emergency equipment, as, for example, two microphones and two amplifiers are provided for the loudspeaking communication feature of the system. Either of the microphones may be selected by the attendant at the control station and either of the amplifiers, likewise, may be selected. In addition, the amplifiers are arranged to be automatically switched in the event that the regular amplifier is not operating properly. A signaling system is provided which informs the attendant of this change-over.

Since reliability of communication is the prime characteristic of this system, numerous devices and systems are provided for periodically or continuously testing the lines and the equipment for possible faults. A continuous open-circuit test is provided by a relay which is responsive to a decrease in line current below a predetermined amount to actuate a signal at the control station and at the outlying station associated with that line. Similarly, a continuous short-circuit test is provided at each station. At the control station a relay responsive to an increase in line current above a predetermined amount operates to provide an indication of the short-circuit condition of the line. It is desired to utilize a source of current for the lines which is to be used for other purposes and which requires that no ground be connected to this source of energy. It is desired to provide an indication of ground conditions on any of the line conductors, and to provide this protective feature a testing circuit is arranged to test periodically at frequent intervals each conductor of each line for ground condition. This is accomplished by the use of suitable switch mechanism which disconnects each line from the common battery source and together with an auxiliary source applies a ground test to each conductor. Upon occurrence of any ground condition a suitable indication is provided at the control station.

Loudspeaking communication is arranged for selective operation with a single outlying station, a group of outlying stations, or all outlying stations. The loudspeaking communication takes priority over ordinary telephone communication, and when the loudspeaking communication system is set into operation means are responsive to this operation to disconnect at the control station the telephone set and to disconnect at each of the outlying stations the telephone set. The loudspeaking communication is in only one direction from the control station to the outlying stations. In order that there be no delay, particularly when a group of stations or all stations are being called, in determining as to whether each of the called stations has received the communication, each outlying station is provided with means for acknowledging the loudspeaker communication. This means will require a minimum of attention and operation on the part of an attendant at the outlying station and will require no immediate attention from the attendant at the control station. This is accomplished by providing an impulse transmitting device which transmits a series of impulses to the control station. This may comprise a dial actuated trans-

mitter which sends a predetermined number of impulses. At the control station these impulses are received by an energy storage circuit including a capacitor which is charged to a predetermined value whenever the proper number of impulses has been received from an outlying station. In response to these, a signal is displayed at the control station which at a later time may be released by the attendant at the control station.

10 The control station is provided with a plurality of amplifiers each of which is tested at frequent intervals by a testing arrangement which transmits a series of audio frequency impulses through each amplifier, one at a time. If an amplifier fails to transmit a certain number of these impulses at a predetermined volume level an indication will be given that the amplifier is not operating properly. If during test the normally used amplifier is not operating properly, the standby amplifier will be switched automatically into the operating circuit and an indication will be given accordingly.

20 In addition to the frequent periodic tests of the amplifiers at the control station, periodic tests of lesser frequency are provided for the entire loudspeaking communication equipment of the system. At these times each of the amplifiers is again placed into operation, one at a time, 25 and a series of audio frequency impulses is transmitted to each of the outlying stations. The receipt of these impulses at the outlying stations is acknowledged by the same impulse transmitting arrangement by which loudspeaking voice 30 communications are acknowledged. Thus periodically operativeness of the entire communication system is determined.

35 In addition to the telephone communication and the loudspeaker communication provided between a control station and each of a plurality of outlying stations, there is provided a group of stations which are arranged to receive only loudspeaker communications. Such stations, for example, may be the fire commissioner, water and power companies, newspapers, etc., which, however, do not require the elaborate equipment necessary to insure service reliability. Such stations are arranged to receive all loudspeaker communications whether directed to a single outlying station, a group of outlying stations, or all of the outlying stations.

40 In order that a single amplifier might be used to feed any one or more of a plurality of lines without requiring isolation equipment such as isolating amplifiers for each line, a method of coupling the lines to the amplifier is provided so that the speech power delivered to each of the lines will be substantially independent of the number of lines connected to the amplifier and 45 also independent of the condition of the various connected lines. Thus, for example, if at a time when loudspeaker communication is being directed to all of the outlying stations, and one of the lines is either short-circuited or grounded, there will be no appreciable effect upon the amplifier at a control station. This is accomplished by providing an amplifier having a slightly greater amplification factor than would be required if isolation devices or circuits were used 50 and by operating the amplifier into a terminating resistance which is low compared to the parallel impedance of the various lines. Each of the lines is provided with a series impedance which is large compared to the parallel impedance of the line but not sufficiently large to appreciably

increase the power required per line to maintain a predetermined level to the line itself.

In order that power be available at all times for the communication system, auxiliary power equipment is provided at the control station and at each of the outlying stations. Whenever the auxiliary power equipment at any station is automatically switched into service due to the failure of the primary or commercial power source, an alarm indication is given which must be acknowledged by the attendant at the station. If the failure of a primary energy source is merely an interruption, or is of such nature that the attendant is not required to take steps to correct the fault, nothing further need be done, but when the primary power source is restored to service an alarm indication will again be given which requires acknowledgment on the part of the attendant so that all equipment may be restored to its original operating condition.

The novel features believed to be characteristic of this invention are set forth with particularity in the appended claims. The invention, both as to its organization and method of operation, together with further objects and advantages thereof, will be understood more readily by reference to the following description taken in connection with the accompanying drawings in which Figs. 1 to 9, inclusive, when combined in the manner illustrated in Fig. 11, illustrate a communication system embodying the present invention; and Fig. 10 diagrammatically illustrates certain connections forming a part of this system.

Telephone communication system

The present invention, which is particularly adapted for use by such organizations as fire departments and police departments, is arranged to utilize a battery source which is also to serve for certain other purposes which, however, require that no ground be connected to this battery. This battery has been indicated in Fig. 10 by the reference character 462 and certain operations in the system are augmented by an auxiliary battery 463, the negative terminal of which is always connected to the positive terminal of the main battery source. In the drawings the terminals of the regular exchange battery have been indicated by a symbol such as a large circle together with the appropriate polarity indication. The auxiliary battery terminals have been indicated as rather small circles together with the appropriate polarity indication. The system herein shown and described has numerous features which subsequently will become apparent, and for the purpose of portraying the salient features as simply as possible these will be described under separate topic headings. Therefore, while the present system provides also loudspeaking communication for dispatching information to various outlying or remote stations, such as fire houses, ordinary telephone communication is also provided, and this will be the first feature to be described.

The control station is provided with a telephone set 101 connected to a plurality of switching keys. Each key N110 is of the three-position type having make contacts 111 and 112 and a break contact 113. The make contacts 111 and 112 are connected to the conductors 102 and 103 which are connected through break contacts 256 and 258 of a relay N250 to the primary winding of a transformer N228. The transformer N228 is provided with two secondary windings N219 and

N229, the adjacent points being interconnected by a capacitor N232. The outer extremities of the transformer windings N219 and N229 are connected to the conductors N233 and N234 of a telephone line which extends to an outlying station N400. Only one communication channel has been shown in the drawings as extending between the control station and an outlying or remote station, although it is to be understood that the system contemplates the use of a number of remote stations and hence certain equipment, such as the lines and associated relay apparatus, will be multiplied by the total number of stations, which may be N in number, to be provided for the system. At the outlying station N400 the telephone conductors N233 and N234 are connected through the break contacts 443 and 444 of a relay LS440 to a telephone set which includes the usual induction coil 434, a transmitter 435, a receiver 436, and a receiver switch 437. The receiver switch 437 is provided with the contacts 438 and 439 which are arranged to interrupt the circuits through the transmitter and receiver and the two windings of the induction coil. Interposed between the said contacts 439 and one winding of the induction coil 434 is a capacitor 458 arranged to be short-circuited by a switch 459. The outlying station is also provided with a source of energy 414 in the form of a storage battery arranged to be maintained at proper charge by a charging device 415 which is energized from the conductors 416 which are connected to a suitable source of commercial power or alternating current. The battery 414 is connected to a choke coil 429 which in turn is connected to the telephone transmitter 435. The common juncture between the choke coil 429 and the telephone transmitter 435 is connected to a capacitor 433 which is connected to the other side of the battery 414. The choke coil 429 and the capacitor 433 serve to smooth out any ripple which might appear across the battery 414 when the charger 415 is bringing the battery up to proper energy level.

If the attendant at the control station desires telephone communication with an attendant at the outlying station N400 the first operation performed is to throw the switch N110 to the left, thereby to break the contact 113 which, it will be seen, is connected to the positive terminal of the central source of energy. This interrupts the connection between the positive terminal of the regular exchange battery and a conductor 104 which extends through break contacts 323 of a slow-operating relay N320 to a relay NLO300. The circuit from the relay NLO300 may be traced through the conductor 235, the winding N229 of the transformer N228, the line conductor N234 to the outlying or remote station where the conductor N234 is connected to a winding 449 of a transformer 454. The other terminal of the transformer winding 449 is connected through interrupter contacts 447, a relay LO430, a relay LS440, the winding 448 of the transformer 454 to the other line conductor N233 which extends back to the control station. Conductor N233 is connected through the transformer winding N219, the conductor N265, a relay NLS310, the break contacts 325 of the relay N320, and a resistor 313 to the negative side of the control station battery. The relays NLO300 at the control station and LO430 at the outlying station are arranged to release their armatures whenever the line current falls below a predetermined value. As will subsequently become apparent, these relays form a

part of a continuous testing arrangement for determining the occurrence of an open-circuit condition on the telephone line. The actuation of the key N110 at the control station which brought about the release of these two relays is, however, for the purpose of notifying the attendant at the outlying station that communication is being desired. The relay LO430 at the outlying station, therefore, drops its armature so that the break contact 432 thereof is closed. The break contact 432 is connected in a circuit which extends through break contact 452 of a key 450 to a bell 453, which in turn is connected through the make contacts 421 of a relay 420, which contact is connected to one side of the alternating current source 416. The other side of the alternating current source 416 is connected through the make contact 423 of the relay 420 to the armature of the break contact 432 of the relay LO430, and hence alternating current energy is supplied to the bell 453 thus giving an audible signal to the attendant. The attendant knows that when the signal given by the bell 453 is of short duration, or is intermittent, the control station is calling. The bell 453 also serves to indicate certain abnormal conditions which subsequently will become apparent. The attendant at the control station having for a short interval thrown the switch N110 to the left now throws the switch to the right which is talk position, wherein the contacts 111 and 112 are closed to connect the telephone set 101 to the conductors 102 and 103, which in turn are connected as previously described with the telephone line extending to the outlying station. As soon as the switch N110 is actuated to permit the break contact 113 to close, the relays NLO300 at the control station and LO430 at the outlying station again pick up their armatures, thus restoring these circuits to their previous conditions. The attendant at the remote station N400 thereupon removes the receiver 436 to close the hook switch 437 whereby communication may now be had between the two stations.

If the attendant at the outlying station N400 desires to signal the attendant at the control station, the receiver 436 is lifted to actuate the hook switch 437 and the switch 459 is momentarily closed, which places a short-circuit across the line conductors N233 and N234. A circuit may be traced from the switch 459 through the make contacts 438 and 439 of the switch 437, the receiver 436, the break contact 444 of the relay LS440, the conductor N233 which, at the control station, is connected through the winding N219 of the transformer N228, the conductor N265, the relay NLS310, the break contact 325 of a relay N320, and a resistor 313 to the negative side of the central or regular exchange battery. The other or positive terminal of the battery is connected through the break contact 113 of the switch N110, the conductor 104, the break contact 323 of the relay N320, the relay NLO300, which is connected through the conductor 235, the transformer winding N229 of the transformer N228 to the line conductor N234 which, at the remote station N400, is connected through the break contact 443 of the relay LS440 and one winding of the induction coil 434 to the switch 459. The relays NLS310 at the control station and LS440 at the outlying station are of the marginal type arranged to be energized whenever the line current exceeds a predetermined amount, which is the condition obtained by an action such as the closing of the switch 459 at the remote

station. Thus at the control station the relay NLS310 is actuated, thus closing make contacts 311 which are connected between the positive side of the central energy source and a conductor 312 which extends through the signal lamp N524 and break contacts 513 of a switch 510 to an alarm or buzzer device 527 which is connected to the negative side of the regular exchange battery. Thus the signal lamp N524 is illuminated which indicates a line short on the telephone line extending to the outlying station N400, since a number of these lamps are provided, each for a different telephone line. The audible signal or buzzer 527 is connected in common circuit relation to all of the various signal lamps which indicate the line-short condition. The closing of the switch 459 at the outlying station N400 causes relay NLS310 at the control station to operate. The signal lamp N524 indicates which station is calling and this call is acknowledged by throwing the corresponding key N110 to the talk position and answering the call.

Loudspeaking communication system

Loudspeaking communication is also provided between the control station and one or more of the remote stations. For this purpose there is provided at the control station certain equipment which includes a microphone 105 and a stand-by microphone S105, either of which may be used by throwing a switch 120 in the proper direction to close contacts 122 or 124. The microphones are arranged to be connected by a pair of conductors 107 which includes a series resistor or impedance 106 to an amplifier 201 or a stand-by amplifier S201. The two microphones and two amplifiers are provided so that in the event one of the devices fails to function properly the other device will be available to insure reliable communication for the loudspeaking dispatching system. The amplifier 201 is normally the amplifier used and the output thereof is connected to a resistor 225, the value of which is relatively low as compared to the impedance of any or all of the telephone lines which may be connected to the amplifier. The impedance or resistor 225 is connected to the break contacts 216 and 218 of a relay 210. These contacts are each connected to resistors N223 and N224 which have a value which is relatively high compared to the parallel impedance of all of the telephone lines. These resistors N223 and N224 are arranged to be connected in series with their corresponding telephone lines as is the case when the make contacts 255 and 257 of a relay N250 are closed to connect the amplifier 201 to the transformer N228. A plurality of individual keys corresponding to the individual telephone lines and remote stations is provided. These keys N507 each have a break contact 508 connected to a conductor 518, and a make contact 509 connected to the positive terminal of the regular exchange battery. The switch arm of the switch N507 is connected to a conductor 254, which is connected through a signal lamp N517 to the negative terminal of the regular exchange battery, and also to relay N250 which is also connected to the negative terminal of this same battery.

It will now be assumed that the attendant at the control station desires to call the remote station N400, whereupon the switch N507 is actuated thus to supply potential to the signal lamp N517 and to the relay N250. The relay N250, upon being actuated, closes make contact 251 to supply energy to a relay 600 which is provided with a plu-

rality of make contacts such as 601, 602 and 603 which are arranged to connect a group or groups of stations to the amplifier whenever the control station communicates with any one or more of the remote stations. The purpose and operation of this arrangement will subsequently be described. The relay N250 closes contacts 252 and supplies potential to a conductor 238 which extends to one of a plurality of contacts cooperating with a switch arm 374 which is arranged in a testing circuit which also will be described later. The relay also closes contacts 253 connected to conductors 236 and 237 which are arranged to short-circuit a relay 760 which also forms a part of the testing circuit. The relay N250 breaks contacts 256 and 258 and makes contacts 255 and 251, thereby connecting the transformer N228 through the resistors N223 and N224 to the amplifier 201, provided that this amplifier 201 has not been switched out of service. If the amplifier 201 has been switched out of service the amplifier S201 is in service by virtue of operation of the relay 210 which will close the contacts 215 and 217. At the time that the relay N250 operates, contact 254 is closed to complete a circuit from the positive side of the auxiliary battery supply 463 through a circuit including a resistor 227, the winding N229 of the transformer N228, the conductor N234, the winding 449 at the outlying station, the contacts 447, the relay LO430, the relay LS440, the winding 448 of the transformer 454, the other line conductor N233, back to the control station, through the transformer winding N219, the conductor N265, the relay NLS310, the break contact 325 of relay N320, a resistor 313 to the negative side of the regular exchange battery, the positive terminal of which is connected to the negative terminal of the auxiliary battery 463 shown in Fig. 10. This, therefore, connects into circuit the auxiliary battery 463 thereby to produce an increase in the current flowing in the line circuit, which causes the marginal relays NLS310 at the control station and LS440 at the remote station to be actuated.

At the outlying station the relay LS440 closes contacts 441 which are connected to an amplifier 461 to complete a circuit which may be in the anode power supply of the amplifier. The contacts 442 are opened which are connected in a circuit including a resistor 456 normally connected across the conductors extending between the amplifier 461 and the loudspeaker 457 so as to prevent, during non-operation of the loudspeaking communication system, the reproduction of certain inherent amplifier noises which may, for convenience, be called singing. At the control station a switch 130 is actuated to the left to close both contacts 131 and 132. This completes two circuits from the positive terminal of the regular exchange battery, one of which includes a conductor 136 which extends to a relay 830 which closes its contacts 831 and 832 to supply energy to an audio frequency tone generator 845. The tone generator 845 is connected through a resistance or impedance network 825, 826 to a pair of conductors 123 and 124 which are connected across the resistor 106 which is in series with one of the microphones, such as 105, and hence is effectively across the input of one of the amplifiers, such as 201. Thus audio frequency energy from the tone generator 845 is being supplied to the amplifiers. At the same time the actuation of the switch 130 has completed a circuit from the positive terminal of the regular exchange battery through the contact 131 and a conductor 118 to a relay 220 which

is connected to the negative side of the regular exchange battery. The relay 220 thereupon closes its make contacts 221 and 222, the latter being connected in a circuit including break contact 214 of relay 210, and in the anode current supply circuit of the amplifier 201. If, for example, the stand-by amplifier S201 were in operation, the relay 210 would be energized so that contact 214 would be broken and contact 213 would be made, whereby the closing of the contacts 221 of the relay 220 would complete the anode current supply circuit of the stand-by amplifier S201. Thus audio frequency energy is now passing through one of the amplifiers and is being transmitted through the amplifier at the called station to the loudspeaker. The attendant at the outlying station thereupon awaits the communication to be expected from the control station.

The attendant at the control station makes the necessary dispatch over the loudspeaking system to all remote stations connected to the amplifier at that time. The dispatcher, however, must know whether or not each of the stations thus connected has received and understood the dispatch given. In order that an acknowledgment of the dispatch shall not appreciably delay the execution of the action required by the dispatch, means are provided at each outlying station for acknowledging the dispatch. This means preferably comprises a dial having a single finger hole corresponding to the zero digit. This dial actuates the dial make and break contacts 447 to transmit a predetermined number of pulses over the telephone line comprising the conductors N233 and N234 to the control station. Since the contacts 447, when opened, place an open-circuit condition on the line, the relay NLO300 at the control station will respond to this momentary open-circuit condition each time that a pulse is transmitted. Thus the contact 301 is broken which is connected by conductor 302 to a slow-release relay N730 and to a rapid-release relay N720 which is connected through the contact 731 of the relay N730. Because the relay N730 is of a slow-release nature, the armature thereof does not move and hence contact 732 is not made and contact 733 is not broken so that the line-open indication lamp N519 is not illuminated. The relay N720, however, responds to the interruptions of the dial at the outlying station so that the break contact 721 is completed a predetermined number of times to connect the positive terminal of the regular exchange battery through a resistor 734 to a capacitor 712, one side of which is connected to the negative terminal of the regular exchange battery. The capacitor 712 is so chosen that after a predetermined number of releases of the relay N720, whereby the contacts 721 are closed, the capacitor 712 will accumulate a charge having a voltage sufficient to bring about energization of relay N710, whereupon its contacts 711 will be closed thereby to illuminate the lamp N525 which in turn is connected through the contacts 511 of a key 510 to the positive terminal of the regular exchange battery, whereupon the relay N710 is locked into operation. The illuminated lamp N525 therefore constitutes an acknowledgment indication that the corresponding outlying station, such as N400, has received and understood the dispatch. A number of lamps similar to N525 are each illuminated in response to each of the outlying stations returning their acknowledgment. The attendant at a subsequent time may release all of the acknowledgment lamps, such as N525, and all of the relays corre-

sponding to N710, by throwing the switch 510 to the left whereby the contacts 511 will be broken, thus to interrupt the circuits and restore them to original condition.

In a system of this sort it furthermore is necessary to provide an arrangement whereby any loudspeaking dispatch communication service takes precedence over any telephone communication. In the previous description of communication to an outlying station it will be remembered that the attendant actuated a key N507 to the left, thereby to energize the relay N250 which interrupted the break contacts 256 and 258 which were connected to the conductors 102 and 103 extending to a key N110 whereby the attendant's telephone set could be connected. It therefore is apparent that the operation of the relay N250 serves to disconnect from any telephone line the telephone set at the control station. At the same time the relay N250 completed the contact 254 thereby to supply additional potential to the telephone line so as to bring about the operation at the outlying station of the relay LS440. The operation of the relay LS440 opens the contacts 443 and 444 thereby disconnecting the telephone transmitter and receiver from the telephone line conductors N233 and N234. This operation of course occurs at all stations which are arranged to be connected to the control station by one or more selective switching means at the control station such as the key N507 or certain other keys whereby certain groups of stations or all stations in the system may be connected to the amplifier at the control station.

It may be desirable at times to call a certain group of stations and for this purpose a plurality of group keys G500 is provided. The key G500, when actuated, closes contacts 501 and 502, the latter being connected to a signal lamp G503 corresponding to that group. The closing of the contacts 501 places the positive terminal of the regular exchange battery on a conductor 536 which extends to a group relay 610. Each group relay is provided with a plurality of contacts, one of which is shown at 611. The closing of each of the contacts corresponding to the contacts 611 brings about the operation of corresponding relays such as N250 for each station included in that particular group. This will be appreciated by following the circuit which extends from the contacts 611 through the conductor 518, the break contact 508 of one of the keys N507, the conductor 254, to a relay N250. Therefore the corresponding relay N250 is actuated in response to the operation of the relay 610.

If it is desired to have all stations connected at the same time to the control station, a single key such as AS504 is actuated to place the positive terminal potential of the regular exchange battery upon the conductor 537 whereby the all-station pilot lamp AS505 will be illuminated. The conductor 537 is connected to the all-station relay 620, of which sufficient relays are provided so as to connect all of the stations into the circuit. This is accomplished by having such relays as the all-station relay 620 connect the positive potential of the regular exchange battery through a plurality of contacts such as 621, conductor 518, the break contact 508 of the switch N507, the conductor 254, to one of the relays N250. Thus when the all-station switch AS504 is actuated, all the relays corresponding to the relay N250 are actuated thereby connecting all of the telephone lines to the amplifier 201. Each

station in turn will acknowledge the dispatch whereby the corresponding lamp N525 is illuminated.

Whenever an individual station, such as N400, or a group of stations such as controlled by the relay 610, or all stations such as controlled by the relay 620 are connected to the amplifier at the control station, a common group of stations is also connected to the amplifier. Such group may comprise a plurality of stations corresponding to N400 which are controlled by one of a plurality of contacts corresponding to contacts 603 of the relay 600, and also a number of other stations controlled by the contacts 601 and 602 of the relay 600. This latter group of stations comprises stations such as 540 each provided with an amplifier 541 and a loudspeaker 542 connected by conductors 543 through resistors 631 and 632 to the contacts 601 and 602 of the relay 600. For example, such loudspeaking stations corresponding to 540 may include stations such as the newspapers, the water and power companies, etc.

Continuous line testing

Service reliability being one of the prime characteristics of a system of this sort requires that each of the telephone lines to the remote stations be maintained in proper operating condition. In order to determine this operating condition an arrangement is provided for continuous line testing having open-circuit and short-circuit conditions. At the control station each line corresponding to the conductors N233 and N234 is interconnected with relays corresponding to NLO300 and NLS310. The relay NLO300 continuously detects a condition corresponding to open-line condition since the relay NLO300 will drop its armature as soon as the line current drops below a predetermined value thus opening its contact 301 which is connected to a conductor 302, thereby to deenergize relays N730 and N720. The relay N730 opens its contact 733 and closes its contact 732, which latter contact is connected to conductor 521, whereby positive potential is supplied to the conductor to illuminate the line-open indication lamp N519 which is connected through break contact 515 of the switch 510 to an audible alarm or buzzer 528 connected to the negative terminal of the regular exchange battery. Thus the signal lamp N519 indicates the particular line which has an open-circuit condition thereon and the general audible alarm device 528 signals the operator that such condition is present.

The control station is also informed of a line-short condition occurring on each telephone line by operation of the corresponding relay NLS310 which is arranged to be actuated whenever the line current is increased above a predetermined value. When this occurs the contacts 311 are closed, thereby to place the positive potential of the regular exchange battery upon a conductor 312 which is connected to illuminate the line-short indicating lamp N524, which in turn is connected through the break contact 513 of the switch 510 to a common audible alarm 527 which signals a line-short condition. Whenever either a line-short condition or an open-line condition occurs the attendant at the control station having noted such condition may thereupon throw the switch 510 to the right thereby to acknowledge the trouble condition and to deenergize the particular audible and visual signal devices.

At the outlying station a relay LO430 is ar-

ranged to be deenergized whenever the line current drops below a predetermined amount so that the contact 431 is opened and the contact 432 is closed. The closing of the contact 432 completes a circuit from one side of the alternating current source 416 through the break contact 423 of the relay 420, the contacts 432 and 452 to the alarm bell 453, which in turn is connected through the contact 421 of the relay 420 to the other side of the alternating current source 416. The outlying station attendant therefore becomes aware of some difficulty on the line and this may be acknowledged by throwing the key 450 to open the contact 452 and to close the contact 451. If subsequently the line is restored to its original condition the relay LO430 will be energized, thereby closing its contact 431 so as to again supply alternating current energy to the bell 453. The attendant thereupon acknowledges the return of the line to its normal condition by throwing the key 450 to open the contact 451 and to close the other contact 452.

If now, however, a line-short occurs across the conductors N233 and N234 the line current at the control station will rise above a predetermined amount, thereby to actuate the relay NLS310. This is due to the fact that the control station is provided with the regular exchange battery and the short-circuit of course occurs at some point just beyond the control station. Due to the short circuit, the control station exchange battery cannot supply line current to that portion of the line beyond the short circuit, and hence at the outlying station the line current again decreases below a predetermined amount thereby causing the relay LO430 to drop out of the circuit. The alarm 453 therefore is actuated to indicate that either a line-open or line-short condition is present between the outlying station and the control station.

Periodical line testing

Because the control station exchange battery is ungrounded, it is necessary to provide a means for periodically testing each conductor of each telephone line for ground condition by apparatus which does this by the use of an auxiliary battery. The control station is provided with a power supply which includes a connection to a commercial source of energy, and an auxiliary power supply is provided which is automatically switched in whenever the commercial source fails. This source of power, which supplies energy to the amplifiers 201 and S201, is connected by a switch 824 to a timing circuit which includes a synchronous motor 827 which drives through suitable gearing indicated by the rectangle 828, a pair of cams 835 and 829. The cam 835 is driven at a rate to provide one revolution every few minutes, for example, every five minutes, and the other cam 829 is driven at a rate to provide one revolution in several hours, for example, every four hours. The cam 835 has a detent whereby a switch 836 is closed which is in a series circuit with switch contact 821 of a relay 820 which is also energized from a source of power connected to the power switch 824. The operation of the cam 835 therefore completes a circuit from the positive terminal of the regular exchange battery through the relay contact 821, the switch contact 836, and relay contact 822 to the parallel connected relays 740 and 750, the latter relay being a slow-operating relay. Since the relay 740 operates be-

fore the relay 750 a circuit is completed from the positive terminal of the regular exchange battery through the make contact 741 of this relay, the break contact 751 of the slow-operating relay 750 to relay 760 which is connected through a current limiting resistor 762 to the negative side of the exchange battery. At the same time a circuit is also completed by way of the conductor 362 to a stepping magnet 370 which is connected to the negative terminal of the exchange battery. The wipers 372, 373 and 374 associated with the magnet 370 are arranged to advance one step when the magnet 370 is restored. When relay 750 operates after a short delay contacts 751 are opened to interrupt the circuit for magnet 370 thereby allowing this magnet to restore and move the wipers one step in the counterclockwise direction. As soon as the magnet 370 has moved the switch arms forward one step, one of a plurality of relays, such as N320, is actuated so that in response the contacts 322 are made, thereby to energize a slow-operating relay 340. The relay N320 has also interrupted contacts 323 and 325 thereby disconnecting the telephone line conductors N233 and N234 from the regular exchange battery, and these conductors have been connected by the closure of contacts 324 and 326 of the relay to an auxiliary test battery 303. The contacts 324 and 326 are made prior to the interruption of the contacts 323 and 325, thereby to prevent any false release or operation of the relays NLO300 and NLS310, respectively. In place of the resistor 313 being connected in series with the relay NLS310 there is now connected a resistor 327. The slow-operating relay 340 completes a circuit from ground through a rapid-operating relay 350, relay contacts 341, relay contacts 333, a current limiting resistor 328, test battery 303, contacts 324, relay winding NLO300, conductor 235, winding N229 and line conductor N234. At the same time that the slow-operating relay 340 closed its contacts 341 the contacts 342 were closed which energized a slow-operating relay 330 which operates a short time later and interrupts the contacts 333 and closes contacts 332, thereby to connect the rapid-operating relay 350 from ground through the contacts 341 and 332 to a current limiting resistor 329 which is connected through the test battery 303, resistor 327, contacts 326, winding of relay NLS310, winding N219 to the line conductor N233. The relay 350 is thus successively connected between ground and each of the line conductors N234 and N233 to test for ground. If the line conductor being tested is grounded, the test battery 303 will operate relay 350.

When the relay 330 closes contacts 331 a slow-operating relay 360 is energized closing contacts 361 to complete a circuit from the positive terminal of the exchange battery through relay contacts 321, 381, 361 and magnet 370 to the negative terminal of the exchange battery. Magnet 370 operates to condition wipers 372, 373 and 374 for operation. Relay 360 in closing its contacts 363 completes a circuit for energizing the slow-operating relay 380. Relay 380, upon operating shortly thereafter, interrupts at contacts 381 the energizing circuit for the magnet 370, whereupon the wipers 372, 373 and 374 are moved one step in the counterclockwise direction and into engagement with contacts terminating the circuit for the next succeeding relay corresponding to relay N320.

After the initial starting pulse has been re-

ceived by the magnet 370 from relays 740 and 750, the continued intermittent operation of the wipers 372, 373 and 374 is maintained by the magnet 370 entirely under the control of relays N320, 330, 340, 350, 360 and 380. These latter relays perform in the above-explained manner, causing tests to be made upon all of the lines in the system in succession with the exception of those lines which are in use for the transmission of loudspeaking service. After one half revolution of the wipers the opposite ends of the wipers 372, 373 and 374 engage the normal contacts and as no relay corresponding to relay N320 is connected thereto, operation of the wipers is discontinued and a testing cycle is completed. A new cycle is initiated as explained above by operation of the timing cam 835, whereby contacts 836 are again closed to complete a circuit for relays 740 and 750.

If, however, a ground condition is found on either of the line conductors N233 or N234 this will be reported prior to the operation of the slow-operating relay 360. Since the relay 350 will close its contacts 351, whereby the switch arm 373 will engage conductor 334 which is arranged to energize relay N700, the relay N700 will close its contacts 701 to supply potential to a conductor 535 which is connected through a key N506 to the positive terminal of the regular exchange battery, thereby locking in the relay N700. The relay N700 also closes its contacts 702 connected to the conductor 523 connected to a signal lamp 522, which is connected through contacts 515 of the switch 510 to an audible alarm device 528 which in turn is connected to the negative side of the regular exchange battery. The attendant at the control station having become aware of the ground condition on one of the telephone lines may acknowledge this by actuating the switch N506 which will deenergize the relay N700 thereby also to deenergize the audible alarm device 528 and the visual signal N522. The ground condition encountered on one of the lines, however, must be cleared up, and until this is done a periodic audible warning signal will be given every five minutes by energization of the audible signal 115, as will be described hereinafter.

It will be remembered that at the time that the cam 835 closed the switch contacts 836, that the relays 740 and 750 were energized in parallel. The relay 740, however, is quicker to operate than the relay 750 so that the contact 741 was made prior to the breaking of the contact 751. Energy therefore was supplied for a short time interval to the relay 760 which attracted its armature thereby to close the contacts 761 so that the relays 240 and 810 were energized. These relays are in parallel and shortly after energization are locked into operation. The relay 810 is also in a circuit which includes a motor 837 which drives a gear box 838 to which is attached a plurality of cams 839, 843 and 846. The cam 839 actuates a switch 840 which, by the making of the contacts 841, locks into operation the relays 240 and 810 and the motor 837. If during a previous test by the timing equipment 800 one of the lines was found to have a ground thereon a corresponding signal was indicated by the lamp N522 and the alarm device 528, which was acknowledged by the throwing of the switch N506. If the attendant operates the switch 510 to the right instead of the key N506 when a grounded line is indicated by the lamp N522 and the buzzer 528, the buzzer 528 will be disconnected at contact 515 but the lamp N522 will remain illuminated from

a circuit including the negative terminal of the regular exchange battery connected through contact 516. Accordingly, when the next test period occurs, the acknowledgment switch 510 having been thrown to the right has closed the contacts 512 thereby to complete a circuit from the positive terminal of the regular exchange battery through conductor 131, the alarm device 115, the conductor 128, the contacts 241 of the relay 240, and a resistor 245 to the negative terminal of the regular exchange battery. Thus the attendant at the control station is intermittently at five minute intervals warned of line trouble on one or more of the telephone lines.

If at the time that the timer 800 is to make its periodic five minute tests any one or more of the telephone lines is in use, the ground testing will not be applied to the lines in use and, furthermore, at that time there will be no energization of the line trouble audible alarm 115. If any one of the lines is in use in conjunction with the loudspeaking system, the corresponding relay N250 will be energized whereby the contacts 252 and 253 thereof are closed. The contact 252 completes a connection from the positive terminal of the regular exchange battery through the conductor 238 to the switch contacts cooperating with the switch arm 374. The switch arm 374, upon engaging a contact being supplied with positive potential, will thereupon again energize the stepping relay 370 so that it advances the switch arms 372, 373 and 374 to the next succeeding contact, thereby preventing the remaining apparatus which includes the auxiliary battery and the relays N320, 330, 340, 350, 360 and 380, from operating. Other lines, however, which do not have a potential applied through conductors corresponding to the conductor 238 are subjected to the ground test. At the same time that relay N250 is energized, thereby closing its contacts 253, the conductors 236 and 237 are connected together which are across the relay 760, thereby short-circuiting this relay. Thus whenever the timer 800 begins its periodic operation, thereby energizing relays 740 and 750 which normally would provide a short period of energization of the relay 760, which, however, has been short-circuited because of loudspeaking communication being carried on over one or more of the telephone lines, will not be operated and hence the relays 240 and 810 are not energized. As a result of this the motor 837 also is not energized and hence that part of the testing apparatus does not come into operation as long as the loudspeaking equipment is used.

Periodic amplifier testing

In order to insure reliability of operation of the equipment at the control station, in addition to the line ground tests, there is also provided an arrangement for testing each of the amplifiers 201 and S201. The timer 800 having closed the contacts 836 of the switch operated by the cam 835, has energized relays 740 and 750 so that for a short interval the relay 760 has been energized so as to lock into circuit the relay 810 and the motor 837. The relay 240 is also locked into circuit and this relay closes its contacts 244 thereby to energize relay 220 which closes its contacts 221 and 222, whereby the anode circuit of the amplifier 201 is completed thereby conditioning this amplifier for use. At the same time the contacts 243 are interrupted and contacts 242 are closed which momentarily interrupts the circuit of the relay 230 and again closes it. The relay 240 also

prepares a circuit from the negative terminal of the regular exchange battery through resistor 245 and relay contacts 241 to conductor 128 which is connected to contacts 152 and 154 of switch 150.

In the event that prior to the periodic amplifier test the switch 150 has been actuated in either direction to acknowledge the failure of one or the other of the amplifiers, as, for example, by throwing the switch to the left to acknowledge the failure of the regular amplifier, energy is now supplied through the audible signal 116 as the circuit to the relay 230 will have been interrupted by the operation of the relay 210 which changed the operation from the regular amplifier to the spare amplifier. The warning signal given by the signal device 116 is of short duration as it is terminated by the operation of the relay 230 which in this case is in a circuit extending from the positive terminal of the regular exchange battery through contacts 242, the conductor 126 and lamp 114 which is connected to the negative terminal of the regular exchange battery.

The test continues, and motor 837 by means of the cam 839 actuates switch 840 which by contacts 841 has connected in the motor 837 across the regular exchange battery. The switch 840 has also closed contacts 842 to supply energy to an audio frequency tone generator 845, the output of which is connected to a circuit including a pair of resistors 825 and 826, the latter resistor being connected across the conductors 123 and 124. The cam 843 is provided with two groups of detents, each four in number, so as to close the contacts 844 whereby for short time intervals the tone generator 845 will be connected to supply energy to the conductors 123 and 124. The conductors 123 and 124 are connected across the resistor 106 which is in the input circuit to the amplifiers 201 and S201. The cam 846 during one half of its revolution closes contacts 847 which are connected to contacts 811 of relay 810 which are connected to conductor 818 which leads to a relay 900. Therefore the relay 900 is energized so that it closes contacts 902 and 903, the latter contact being connected to conductor 263 which extends to the contacts 261 of a relay 260. The relay 260 is arranged to be energized by suitable vacuum tube circuits connected to receive energy from the loudspeaking amplifier then in use which is connected to the conductors 264. This device, of course, may be any one of a number of suitable arrangements arranged to be responsive to a predetermined volume level of the amplifier, whereupon the relay 260 will be energized. Each time that a short interval of audio frequency is supplied by the tone generator 845 through the conductors 123 and 124 to the input of the amplifier 201, which normally is connected for use, the energy appearing across the output is connected to appear across the conductors 264, thereby to provide an energization of the relay 260 if the amplifier is operating to amplify the received signal up to a predetermined amount. It will be assumed that the amplifier has amplified the first pulse of audio frequency sufficiently to cause operation of the relay 260 whereby the contacts 261 and 262 are closed. The contacts 262 are connected by a conductor 139 to energize a signal lamp 108 thus indicating that the proper volume level of the amplifier has been attained. Further indication of the proper volume of the amplifier may also be provided by conductors 138 connected to an indicating meter 109 which primarily is for the purpose of permit-

ting the attendant at the control station to so regulate the volume of his voice as to provide intelligible reproduction without greatly exceeding normal volume level at which the system is designed to operate. The contacts 261 of the relay 260 having been closed apply positive potential from the regular exchange battery through conductor 263, contacts 903 of the relay 900, contacts 922 of a relay 920, to a relay 925 which is connected to the negative terminal of the regular exchange battery. This brings about energization of the relay 925 which pulls up its armature to close the contacts 926. Positive potential therefore is now applied at both terminals of a relay 920, one potential being supplied through the contacts 926 of the relay 925 and the other potential being supplied through the contacts 902 of the relay 900. The cam 843 continues to rotate so that after a short time the contacts 844 are opened, whereby no longer is there applied to the amplifier any audio frequency energy sufficient to maintain the energization of the relay 260. Thereupon the positive potential appearing on the conductor 263 is no longer applied to the contact 926 of the relay 925. Positive potential, however, is applied from the contacts 902 of the relay 900 to the relay 920 and through the contacts 926 of relay 925 which in turn is connected to the negative terminal of the regular exchange battery, whereby both of these relays are now locked in series circuit. The relay 920, being energized, interrupts contacts 922 and closes contacts 921. The cam wheel 843 continues to advance, whereupon the contacts 844 again are closed thus supplying a short interval of audio frequency energy from the tone generator 845 to the amplifier 201. If the amplifier is operating properly the relay 260 again will be energized, whereupon positive potential will be applied to the conductor 263 and a circuit is now completed from the conductor 263 through the contact 903, the contact 921, the contact 932 to the relay 930 which is connected to the negative terminal of the regular exchange battery. This relay closes its contacts 936 thereby conditioning relay 930 for operation in a manner similar to the operation previously described in connection with the relay 920. As soon as the cam 843 has advanced sufficiently to again open the contacts 844, the relay 930 will be energized thereby to interrupt the contacts 932 and to close contacts 931. At the next succeeding tone impulse delivered to the amplifier 201 the relay 260 again operates to apply potential to the conductor 263 whereby the circuit is now from the conductor through the contacts 903, 921, 931 and 942 to the relay 945 which is connected to the negative terminal of the regular exchange battery. This relay attracts its armature to close contacts 946 thereby to again prepare a circuit for the energization of the relay 940 in a manner similar to the energization of the relays 920 and 930. When the switch 844 is again interrupted the relay 940 will be energized, thereby to interrupt the contacts 942 and to close contacts 941 which are connected to contacts 911 and 901, the latter one having been closed by the operation of the relay 900. The contacts 901 are connected to contacts 971 of relay 970. The relay 970 previously was energized at the time that the relay 810 was actuated.

Relays 970 and 980 each were energized at the time that the relay 810 interrupted contacts 814 and closed contacts 813 which then were connected to the positive terminal of the regular ex-

change battery so as to apply this potential to the conductor 815 which is connected to the relays 950 and 960 arranged in parallel and each connected to the negative terminal of the regular exchange battery. The relay 950 operates more rapidly than relay 960 which is slow-operating. Connection is thereby completed from the positive terminal of the regular exchange battery through contacts 951 to each of the contacts 961, 962 and 963 of the relay 960, whereby the winding 976 of the relay 970 and the winding 985 of the relay 980 is energized thereby to operate these relays. At the same time, prior to the operation of the relay 960 energy is supplied to the contacts 961 to a conductor 531 which extends to an audible alarm device 529 connected to the negative terminal of the regular exchange battery. This audible alarm when continuously energized informs the attendant of a testing condition subsequently to be described. The relays 970 and 980 have the windings 976 and 985 locked into circuit by the completion of the contacts 972 and 982, respectively. The relay 960 being slow to operate may now be assumed to have attracted its armature thereby to open all of its contacts thereby deenergizing the audible signal 529.

It will be remembered that the third audio frequency impulse transmitted to the amplifier 201 has brought about the operation of the relays 940 and 945. A fourth impulse is now transmitted by the subsequent operation of the cam 843 which closes the contacts 844. This fourth impulse causes operation of the relay 260 whereby positive potential is applied to the conductor 263 through the contacts 903, 921, 931, 941 and 901 to the contacts 971 of the relay 970, thereby to energize the winding 975 which is differentially arranged relative to the winding 976 which thereupon will bring about a release of this relay.

The cams connected to the motor 837 by the gear box 838 have now made one-half revolution so that the cam 846 will actuate its switch to interrupt contacts 847 and to close contacts 848, whereby positive potential is applied to a conductor 849 to energize a slow-operating relay 910. Prior to the operation of the relay 910 the relay 900 releases due to the interruption of the contacts 847. During the subsequent rotation of the cam 843 successive intervals of audio frequency energy are supplied from the tone generator 845 to the conductors 123 and 124. The relay 910, having operated, has closed its contacts 814 thereby to supply positive potential to a conductor 119 which is connected to relay 210 which now operates to interrupt the anode supply to the amplifier 201 by opening its contacts 214 and to complete the anode supply to the amplifier 201 by closing its contacts 213. At the same time contacts 216 and 218 are interrupted and contacts 215 and 217 are closed so as to disconnect the output of the amplifier 201 from the conductors 264 and to connect the output of the amplifier 201 to these same conductors. The relay 260 therefore is now arranged to be responsive to the output of the auxiliary amplifier 201 whereby during the successive tone impulses the relay is successively energized to bring about operation of relays 920, 925, 930, 935, 940 and 945 in a manner similar to the previous operation since the circuit arrangement provided by the interruption of the contacts 903 of the relay 900 and the closing of the contacts 913 of the relay 910 is the same as far as these relays are concerned. At the time that the relay 900 was re-

leased all of these relays were deenergized because of the interruption of the contacts 902. For the first current impulse applied to the auxiliary amplifier 201 the relay 910 has prepared a circuit by the closing of its contacts 912 so that at the termination of the first impulse the relays 920 and 925 are locked into circuit. Therefore it may now be assumed that all of these relays have responded to the first three impulses received by the auxiliary amplifier, whereby a circuit is now completed from the contacts 941 of the relay 940 through the contacts 911 of the relay 910 to the contacts 981 of the relay 980. When the fourth tone impulse is received and properly amplified by the amplifier 201 positive potential will again be supplied to the conductor 263 whereupon the winding 984 of the relay 980 will be energized in opposition to the winding 985, thereby to release this relay. If both the relays 970 and 980 are each released after the periodic testing of the amplifiers no indication will be given to the attendant at the control station and the regular amplifier 201 will again be returned to service since the cam 846, upon completion of its revolution, will open contacts 848 thereby to deenergize relay 910 so that relay 210 is deenergized. The cams 839 and 843 having completed one revolution open the output circuit of the tone generator 845 and interrupt the energy supply circuits to the tone generator, the motor 837, and the relays 810 and 240 thus restoring the equipment to its original condition prior to the test.

If the auxiliary amplifier 201 failed to receive and amplify at proper volume level all of its impulses, the relay 980 would not have been released whereby the contacts 983 still would be closed. Upon deenergization of the relay 810 positive potential would be applied through the contacts 814 to conductor 816 which is connected through contacts 983 to conductor 534 which is connected through a signal lamp 532 to the negative terminal of the regular exchange battery thus to provide a visual indication that the auxiliary amplifier is not operating properly. An audible signal is also provided by a connection of a conductor 228 to the conductor 534 whereby positive potential is also impressed upon a conductor 127 connected to an audible signal device 116 which is connected through contacts 153 and 154 of switch 150 and through a resistor 117 to the negative side of the regular exchange battery. The attendant at the control station acknowledges the failure of the spare amplifier by throwing the key 150 to the right, thereby to interrupt the circuit through the audible signal device 116. If at the time that the next five minute testing period is to begin the spare amplifier has not yet been placed in proper operating condition, the relay 240 will be energized thereby to connect the negative terminal of the regular exchange battery through the resistor 245 and relay contacts 241 to conductor 128 which now is connected to switch contacts 152 and 153 to the signal device 116, which in turn is connected by means of conductors 127, 228 and 534, contacts 983, 973 and to conductor 119. The regular amplifier will receive its usual test from the thousand cycle tone apparatus and subsequently the spare amplifier will be tested. This involves the operation of relay 910 which closes contacts 914 thereby to complete a connection between the conductor 119 with the positive terminal of the exchange battery, thus bringing about energization of the signal device 116 for the time interval

required normally to test the spare amplifier. Thus periodically every five minutes the signal device 116 will be energized to remind the attendant at the control station that one of the amplifiers has not yet been restored to normal operating condition.

If it is assumed that the amplifier 201 failed to receive and amplify properly all of its impulses, the relay 970 will not have been released. Upon release of the relay 810 positive potential will be applied through the contacts 814 to the conductor 816 and to both contacts 973 and 974 of relay 970. The latter contact 974 is connected to conductor 533 which in turn is connected through signal lamp S532 to the negative terminal of the exchange battery to indicate that the spare amplifier has been switched into operation. This switching of the spare amplifier was accomplished by the application of positive potential through the contacts 973 of the relay 970 to the conductor 119 which is connected to energize relay 210. The relay 210 by the contacts 213 to 218, inclusive, switches into use the auxiliary amplifier S201. The relay 210 interrupts the contacts 211 thereby to deenergize the relay 230 which is connected by conductor 126 through a signal lamp 114 to the negative terminal of the regular exchange battery. The signal lamp 114 normally is illuminated when the regular amplifier 201 is in use. The deenergization of the relay 230 permits the closing of contacts 231 to supply positive potential to a conductor 127 which is connected to an audible alarm device 116, which in turn is connected through contacts 153 and 151 of switch 150 and through resistor 117 to the negative side of the regular exchange battery. The attendant at the station acknowledges the failure of the regular amplifier by throwing the switch 150 to the left thereby to open the contacts 153 so as to open the circuit to the audible alarm 116. The operation of the switch 150 to the left brings about the closing of contacts 154 which are connected to conductor 128 so that at each five minute interval when the relay 240 is energized potential is supplied from the negative terminal of the exchange battery through resistor 245 and contacts 241 to conductor 128 which is connected through contacts 154 of switch 150 to the alarm 116 which is connected through conductor 127 and contacts 231 of relay 230 to the positive terminal of the regular exchange battery. Thus every five minutes the audible alarm 116 will be energized for a short interval to continue to warn the attendant that the regular amplifier has not yet been placed back in service.

Periodic loudspeaker testing

At greater time intervals, such as several hours, or, for example, four hours, the entire loudspeaking communication system is subjected to a test. The detent on the cam 829 actuates its switch at the same time that the detent on the cam 835 actuates its switch. Therefore relays 740 and 750 are energized in succession and relay 760 is momentarily energized. Relay 760 brings about energization of relay 810 which starts the motor 837. The closing of the switch 834 by the cam 829 completes a circuit from the positive terminal of the regular exchange battery through contacts 821 and switch contacts 836, relay contacts 823, relay contacts 812, to conductor 537 which is connected to relay 620 and also to signal lamp AS505. The signal lamp AS505 is the one which is illuminated either by the testing apparatus or by the attendant at the control station

by the actuating of switch AS504 whenever all of the stations of the system are to be connected to the loudspeaking amplifiers. The relay 620, it will be remembered, operates to cause all of the stations to be connected to the amplifiers by the operation of the corresponding relays N250. Operation of the relay N250 places positive potential through the contacts 252 upon the conductor 238 so that the line ground test apparatus, by preventing the operation of any N320 relay, is not permitted to disconnect any of the lines from the regular exchange battery. The relay N250 also closes contacts 253 thereby placing a short circuit across the relay 760 which, however, has no effect since this relay was energized at the beginning of the cycle of testing prior to the operation of the relays 620 and N250. The motor 837 through the gear box 838 drives the cams 839, 843 and 846 in a manner as was previously described. This brings about energization of the tone generator 845 which transmits a series of tone impulses to the regular amplifier and then to the spare amplifier. When the motor 837 has completed a complete revolution of each of the cams, each of the outlying stations is required to acknowledge the receipt of the test impulses by actuating its impulsing device 441. This produces an acknowledgment at the control station in a manner previously described, whereby the acknowledgment lamp N525 is illuminated. When all of the stations have responded by transmitting the acknowledgment impulses the attendant at the control station may return to normal the signal lamps N525 by actuating the switch 510 to the left to break the contacts 511, which thereupon will bring about the release of each of the relays corresponding to N710.

Auxiliary power sources

The control station and each outlying station is provided with a connection to a regular power source and is provided with an auxiliary source of power. At the control station this power supply has been designated by the rectangle 819 and this power supplies energy to the motor 821, to the amplifiers 201 and S201, and to other equipment such as the anode power supply in the event that the tone generator 845 utilizes vacuum tubes or a vacuum tube amplifier. In order to simplify the disclosure in the present instance, the auxiliary and commercial power supply sources have only been shown at the outlying station N400. An alternating current source is provided for the conductors 416 which are connected to an alternating current relay 420 which completes a circuit through contacts 421 and 423 to the amplifier 461. A relay 410 is also connected across the conductors 416. Whenever the alternating current source connected to the conductors 416 fails or is interrupted, the relays 410 and 420 are deenergized whereby a storage battery or auxiliary power source 414 is arranged to supply energy to the amplifier 461. The relay 410 when deenergized breaks contacts 411 and closes contacts 412 thereby connecting the battery 414 to an inverter 427, the output of which is now connected through relay contacts 422 and 424 to the amplifier 461. Across the output in the inverter 427 there is connected a signal lamp 428 to visually indicate that the inverter and auxiliary power source are in operation. The completion of the contact 412 of the relay 410 also connects through contacts 419 an audible signal device 417 across the battery 414, thereby

audibly indicating to the attendant at the outlying station that the regular power source has failed and that the auxiliary source is now in operation. The attendant at the outlying station may acknowledge this signal by throwing the switch 418 to the right, thereby to close contacts 426. The charge on the battery 414 may be maintained by suitable automatic equipment including a charger 415 which is energized from an alternating current source connected to the conductors 416. If the power supply 414 is again restored to normal alternating current energy will energize the relays 410 and 420, thereby to disconnect the amplifier 461 from the inverter and to reconnect the amplifier to the alternating current source. The operation of the relay 410 disconnects the battery 414 from the inverter 421 and completes a connection with contact 411 which in turn is connected through contact 426 to the audible signal device 417 which now audibly indicates to the attendant at the outlying station that the auxiliary current source is no longer being used. Thereupon the attendant again acknowledges this signal by throwing the switch 418 to the left so that this circuit again is prepared to indicate a subsequent change in power for the communication apparatus located at that station. It of course is understood that the power supply 849 at the control station is similarly equipped with visual and audible alarm devices operating in response to the failure of the commercial power supply to automatically switch the communication equipment to the auxiliary power source. The audible signal is also arranged with an acknowledgment switch so that each time that it is actuated the circuit for the audible signal is prepared to indicate a subsequent change of connection between the communication equipment and one of the power sources.

While one embodiment of the invention has been disclosed, it will be understood that various modifications may be made therein which are within the true spirit and scope of the invention.

What is claimed is:

1. A communication system comprising a control station and a plurality of outlying stations, means providing loudspeaker communication with one or more outlying stations at a time, impulse transmitting means at each outlying station for acknowledging communication received from said control station, means at said control station responsive to said impulses to provide an acknowledgment indication.

2. A telephone system comprising a control station and a plurality of outlying stations, means providing loudspeaker communication with one or more outlying stations at a time, impulse transmitting means at each outlying station for acknowledging communication received from said control station, means at said control station responsive to said impulses to provide an acknowledgment indication, said latter means including a capacitor arranged to be charged by said impulses, and a relay arranged to be actuated by a certain charge of said capacitor.

3. A telephone system comprising a control station and a plurality of outlying stations, means providing loudspeaker communication with one or more outlying stations at a time, impulse transmitting means at each outlying station for acknowledging communication received from

said control station, and means at said control station responsive to said impulses to provide an acknowledgment indication including a capacitor arranged to be charged by said impulses, a relay arranged to be actuated by a certain charge of said capacitor, means for locking in said relay, and signal means for producing an acknowledgment indication.

4. A telephone system comprising a control station and a plurality of outlying stations, means providing loudspeaker communication with one or more outlying stations at a time, impulse transmitting means at each outlying station for acknowledging communication received from said control station, and means at said control station responsive to said impulses to provide an acknowledgment indication including a capacitor arranged to be charged by said impulses, a relay arranged to be actuated by a certain charge of said capacitor, means for locking in said relay, signal means for producing an acknowledgment indication, and means at said control station operable to release said relay.

5. A telephone system comprising a control station interconnected with a plurality of outlying stations by telephone lines, a relay at each outlying station responsive to line current below a predetermined value, means responsive to the operation of said relay to produce a signal indication, and means located at said control station for reducing the line current of a line to an outlying station below said predetermined amount thereby to signal said station.

6. A telephone system comprising a control station interconnected with a plurality of outlying stations by telephone lines, a relay at each outlying station responsive to line current below a predetermined value, means responsive to the operation of said relay to produce a signal indication, and means located at said control station for interrupting for a short time interval the flow of line current to said outlying station thereby to signal said station.

7. A telephone system comprising a control station interconnected with a plurality of outlying stations by telephone lines, a relay at said control station responsive to an increase in line current above a predetermined amount, means responsive to the operation of said relay for producing a signal, and means at each outlying station for increasing the line current above said predetermined amount thereby to signal said control station.

8. A telephone system comprising a control station interconnected with a plurality of outlying stations by telephone lines, a relay at said control station responsive to an increase in line current above a predetermined amount, means responsive to the operation of said relay for producing a signal, and means at each outlying station for short-circuiting said line to increase said line current thereby to signal said control station.

9. In a telephone system comprising a control station interconnecting a plurality of telephone lines, the combination comprising means continuously responsive to a short circuit on a line and for indicating said short circuit, and means continuously responsive to an open circuit on a line and for indicating said open circuit.

10. In a telephone system comprising a control station interconnecting a plurality of telephone lines, the combination comprising means continuously responsive to a short-circuit condition on a line, means continuously responsive to an open-circuit condition on a line, and means for

indicating at each end of said line the occurrence of any such condition.

11. In a telephone system comprising a control station interconnecting a plurality of telephone lines, the combination comprising means continuously responsive to a short-circuit condition on a line, means continuously responsive to an open-circuit condition on a line, automatic means for periodically testing each line for a ground condition, and means to indicate the occurrence of each of said conditions.

12. In a telephone system comprising a control station interconnecting a plurality of telephone lines, the combination comprising means for each line continuously responsive to a short-circuit condition on a line including a relay responsive to an increase in line current above a predetermined amount, means for each line continuously responsive to an open-circuit condition on a line including a relay responsive to a decrease in line current below a predetermined amount, and means controlled by each of said relays for indicating the occurrence of said conditions on said lines.

13. In a telephone system comprising a control station interconnecting a plurality of telephone lines, the combination comprising an ungrounded line current battery, means continuously responsive to a short-circuit condition on a line, means continuously responsive to an open-circuit condition on a line, automatic means for periodically testing each line for a ground condition, said means including a switch for disconnecting each line to be tested from the line current battery and successively connecting each side of the line through an auxiliary battery to ground, and means for indicating the occurrence of any one of said conditions.

14. In a loudspeaker communication system, the combination comprising an amplifier, a stand-by amplifier, automatic means for periodically testing each of said amplifiers in succession, means responsive to the improper operation of said first amplifier during test for placing into service said stand-by amplifier, and means for indicating the improper operation of said first amplifier.

15. In a loudspeaker communication system, the combination comprising an amplifier, a stand-by amplifier, automatic means for periodically testing each of said amplifiers in succession including a source of alternating current, means for transmitting a predetermined series of impulses of said alternating current to each amplifier, means for each amplifier responsive to the failure to transmit at a predetermined volume level said series of impulses, means responsive to the improper operation of said first amplifier during test for placing into service said stand-by amplifier, and means for indicating the improper operation of each of said amplifiers.

16. In a telephone system comprising a control station and a plurality of outlying stations, the combination comprising an amplifier at said control station for loudspeaker communication, a second amplifier, automatic means for periodically testing each of said amplifiers including a source of undulating current, means for transmitting a predetermined series of impulses of said undulating current to each amplifier, and means responsive to the failure of an amplifier to receive a series of impulses or to amplify said impulses a predetermined amount for indicating such failure.

17. In a telephone system having a control sta-

tion and a plurality of outlying stations, the combination comprising an amplifier at said control station for loudspeaker communication with said outlying stations, a stand-by amplifier for loudspeaker communication, automatic means for periodically testing each of said amplifiers in succession including a source of alternating current, means for transmitting a predetermined series of impulses of said alternating current to each amplifier, and means for each amplifier arranged to indicate the failure of an amplifier to receive or amplify a predetermined amount said series of alternating current impulses.

18. In a loudspeaking communication system having a control station and a plurality of outlying stations, the combination comprising an amplifier for said control station, a stand-by amplifier for said control station, an amplifier for each outlying station, automatic means at said control station for periodically testing all of said amplifiers, said means including a source of current, means for transmitting a series of impulses from said source to said amplifiers, automatic means for indicating failure of said control station amplifiers to receive and transmit said impulses, means at each outlying station for transmitting to said control station an acknowledgment of the receipt of said impulses, and means at said control station for indicating the receipt of said acknowledgment.

19. In a loudspeaking communication system having a control station and a plurality of outlying stations, the combination comprising an amplifier for said control station, an amplifier for each outlying station, automatic means at said control station for periodically testing all of said amplifiers, said means including a source of alternating current, means for transmitting a series of impulses from said alternating current source to said amplifiers, automatic means for indicating the failure of said control station amplifier, impulse transmitting means at each outlying station for acknowledging the receipt of said series of alternating current impulses, means at said control station responsive to the impulses received from an outlying station to provide an acknowledgment indication including a capacitor arranged to be charged by said impulses, a relay arranged to be actuated by the charge on said capacitor, and means controlled by said relay for producing an indication.

20. In a loudspeaking communication system having a control station interconnected with a plurality of outlying stations by telephone lines, and an amplifier at said control station, the method of coupling one or a plurality of said telephone lines to an amplifier whereby the power delivered by said amplifier to any coupled telephone line will be substantially independent of the number of lines coupled to said amplifier comprising feeding the output of the amplifier into a terminating resistance of a very low value compared to the value of the parallel impedance of the telephone lines coupled to the amplifier, and increasing the resistance of each line so as to have a large value compared to the value of the combined parallel impedance of all of said lines.

21. In a loudspeaking communication system having a control station interconnected with a plurality of outlying stations by telephone lines, the combination comprising an amplifier at said control station, a terminating resistor connected across the output of said amplifier, said resistor

having a relatively low value compared to the value of the parallel impedance of said telephone lines, a series resistor connected to each conductor of said lines and adapted to be connected between said lines and said terminating resistor, said series resistors each having a value such that the series resistance of each line is large compared to the value of the impedance of all of said lines in parallel.

22. In a loudspeaking communication system having a control station, a plurality of outlying stations, a telephone line for each of said outlying stations, an amplifier at said control station, means for selectively connecting to said amplifier one or a plurality of said lines, a resistor connected across the output of said amplifier, said resistor having a relatively low value compared to the value of the parallel impedance of said telephone lines, and means for connecting in series with each conductor of each line a resistor having a relatively large value compared to the value of the parallel impedance of said telephone lines.

23. In a communication system having a control station, a plurality of outlying stations, a telephone line for each of said outlying stations, means for providing telephone communication between said control station and any one of said outlying stations, means for providing loudspeaking communication between said control station and one or more of said outlying stations at a time including an amplifier connected to a terminating resistor having a relatively low value compared to the parallel impedance of said lines, means for selectively connecting said control station to any outlying station for telephone communication, means for selectively connecting said control station to one or more of said outlying stations including means for interposing between said amplifier and each conductor of a line to be connected to said amplifier a series resistor having a relatively large value compared to the value of the parallel impedance of said lines whereby the power delivered by said amplifier to any connected telephone line will be substantially independent of the number of lines connected to said amplifier.

24. A communication system comprising a control station, a plurality of remote stations, a telephone line for each remote station, means providing telephone communication between said control station and any remote station including a telephone set at each of said stations and selective switching means at said control station to connect said control station with any one of said remote stations, means providing loudspeaking communication between said control station and any remote station including selective switching means at said control station to connect said control station with any one or more of said remote stations, and means responsive to said latter switching means for disconnecting the telephone set at said control station and at each remote station connected with said control station.

25. A communication system comprising a control station, a plurality of remote stations, a telephone line for each remote station, means providing telephone communication between said control station and any remote station including a telephone set at each of said stations, selective switching means at said control station to connect said station with any one of said remote stations, each telephone set at a remote station normally being connected with one of said tele-

phone lines, means providing loudspeaking communication between said control station and any remote station including an amplifier and selective switching means to connect said control station amplifier with any one or more of said remote stations, and means responsive to said latter switching means for disconnecting the telephone set at the remote station connected with said control station.

10. 26. A communication system comprising a control station, a plurality of remote stations each provided with a telephone line, means providing telephone communication between said control station and said remote stations including a telephone set at each of said stations, selective switching means at said control station for connecting said set with any one of said remote stations, means providing loudspeaking communication between said control station and any one or more remote stations including an amplifier and selective switching means for connecting said control station amplifier with any one or more of said remote stations, and means responsive to said latter switching means for disconnecting the telephone sets connected to any telephone line over which loudspeaker communication is about to occur.

15. 27. A communication system comprising a control station, a plurality of remote stations, a telephone line for each remote station, means providing loudspeaking communication between said control station and the selected remote station including an amplifier and selective switching means located at said control station for connecting to said amplifier one or more remote station telephone lines, a group of remote stations arranged to receive all loudspeaking communications emanating from said control station, and means responsive to the operation of said selective switching means for connecting said group of stations to said amplifier whenever any remote station telephone line is connected thereto.

20. 28. A loudspeaking communication system comprising a control station interconnected by telephone lines with a plurality of remote stations, an amplifier located at said control station, a plurality of groups of stations, one common group of stations being arranged to be connected to said amplifier whenever one or more stations are connected thereto, selective switching means at said control station for connecting all of said remote stations, one or more groups of remote stations, or one or more remote stations with said control station amplifier, and means automatically responsive to said selective switching means for connecting said common group of stations to said amplifier.

25. 29. In a communication system having a control station and a plurality of remote stations, the combination comprising communication equipment at each station energized from a source of power, an auxiliary source of power, means responsive to the failure of said first source of power for switching said equipment to said auxiliary source of power and for indicating said operation, and means for manually acknowledging said indication.

30. 30. In a communication system having a control station and a plurality of remote stations, the combination at each station comprising communication equipment normally energized from a source of power, an auxiliary source of power, means responsive to a failure of said first source of power for switching said equipment to said auxiliary source of power and for indicating said

operation, means for manually acknowledging said indication, and means responsive to the restoration of said first source of power for giving an indication of said restoration.

31. In a communication system having a control station and a plurality of remote stations, the combination at each station comprising communication equipment, a source of power normally energizing said communication equipment, an auxiliary source of power, means responsive to a failure of said first source of power for switching said equipment to said auxiliary source of power, and means for indicating a change in power supply for said equipment including a signal and a switch for acknowledging said signal by deenergizing said signal.

32. In a communication system having a plurality of stations, the combination at each station comprising communication equipment, a source of power normally connected to energize said communication equipment, an auxiliary source of power, means for connecting said equipment to either source of power including a relay normally connecting said equipment to said first source of power, said means in response to failure of said first source of power being operative to connect said equipment to said auxiliary source of power and in response to the restoration of said first source of power to reconnect said equipment thereto, and means for indicating a change in the power supply of said equipment.

33. In a communication system having a plurality of stations, the combination at each station comprising communication equipment, a source of power for said communication equipment, an auxiliary source of power, means for connecting said equipment to either source of power including a relay normally connecting said equipment to said first source of power, said relay in response to failure of said first source of power being operative to connect said equipment to said auxiliary source of power and in response to the restoration of said first source of power to reconnect said equipment thereto, audible signal means for in-

dicating a change in the power supply of said equipment, and means for deenergizing said signal thereby to acknowledge said indication.

34. In a communication system having a control station and a plurality of remote stations, the combination at each station comprising communication equipment, a source of power, an auxiliary source of power, means normally connecting said equipment to said first source of power including a relay energized therefrom, said relay upon failure of said first source of power being arranged to connect said equipment to said auxiliary source of power, a signal circuit for indicating a change in the power supply for said equipment including switching means controlled by said relay, a switch connected in said circuit for acknowledging said signal indication by deenergizing said circuit, said switch when actuated being arranged to prepare said circuit to be responsive to a succeeding change in power supply for said equipment.

35. In a communication system having a control station and a plurality of remote stations, the combination at each station comprising communication equipment, a source of commercial power, an auxiliary source of power, means normally connecting said equipment to said commercial power source including a relay energized therefrom, said relay upon failure of said commercial source of power being arranged to switch said equipment to said auxiliary source of power, an audible signal and circuit for indicating a change in the power supply connected to said equipment including switching means controlled by said relay, a second switch connected in said circuit for acknowledging said signal indication by interrupting a circuit to said audible signal, said switch when actuated being arranged to prepare said circuit to be responsive to a succeeding switch of the power supply to said equipment, and a visual signal for indicating whenever said auxiliary power source is connected to said communication equipment.

ROSWELL H. HERRICK.
